Primary Examiner — Mark Goodwin*(74) Attorney, Agent, or Firm* — Fay Sharpe LLP(57) **CLAIM**

The ornamental design for a bracket, as shown and described.

DESCRIPTION

FIG. 1 is a perspective view of a first embodiment of a bracket showing my new design;

FIG. 2 is a front elevational view thereof;

FIG. 3 is a top plan view thereof;

FIG. 4 is a perspective view of a second embodiment of a bracket showing my new design;

FIG. 5 is a front elevational view thereof; and,

FIG. 6 is a top plan view thereof.

The parts illustrated in broken lines in FIGS. 1-6 form no part of the claimed design.
